UNITED STATES PATENT OFFICE.

LEWIS B. WHITE, OF NEW YORK, N. Y., ASSIGNOR TO THE AMERICAN TRADES AGENCY COMPANY, OF SAME PLACE.

AUTOMATIC SAFETY-LOCK FOR LOCOMOTIVE-FURNACE DOORS.

SPECIFICATION forming part of Letters Patent No. 310,005, dated December 30, 1884.

Application filed April 16, 1884. (No model.)

To all whom it may concern:

Be it known that I, LEWIS BOYD WHITE, of the city, county, and State of New York, have invented a new and Improved Automatic Safety-Lock for Locomotive-Furnace Doors, of which the following is a full, clear, and exact description.

The object of my invention is to provide a new and improved safety device for automatically closing and locking the fire-doors of locomotives, in case the locomotive collides with other objects, runs off the track, or in like cases.

The invention consists in a casing pivoted above the fire-door, and provided with a spring, and with an arm for closing and locking the door, which casing can be locked to hold the arm raised by a bolt which is connected with a ball for automatically withdrawing the bolt when the locomotive collides with objects, or runs off the track, &c.

Reference is to be had to the accompanying drawings, forming part of this specification, in which similar letters of reference indicate corresponding parts in both the figures.

Figure 1 is a longitudinal sectional elevation of my improved automatic safety-lock for locomotive fire-doors, the door being closed. Fig. 2 is a side view of the same, the door being open.

A tubular standard, A, provided at its top with a cup-shaped socket, B, adapted to hold a ball, C, is held on the end of a bracket, D, projecting from the rear end plate, E, of the locomotive-boiler. Directly below the bracket D a pin, F, projects from the plate E, on which pin a cylindrical or cup-shaped casing or cap, G, is held to turn, which casing contains a spiral spring, H, having one end secured to the pin F and the other to the casing. The casing G is provided with a curved arm, J, having a short lug, K, on its inner surface at its free end. A stud, L, projects from the outer surface of the casing G. A bolt, M, held loosely in the tubular standard A, is connected by a cord, chain, or wire, N, with the ball C. The fire-door O is provided with the usual pivoted latch-lever, P, for keeping the door closed. The inner end of the lever P is bent outward.

50 The operation is as follows: The spring H

tends to swing and turn the arm J in the direction of the arrow a'. The ball C is placed in the socket B, and the bolt M projects from the lower end of the tubular socket A and rests on the outside or rim of the casing C. The stud L is pressed against the said bolt by the spring H, thus holding the arm J in the position shown in dotted lines in Fig. 1. If the door is opened, the inner bent end of the latch P catches on the lug K of the arm J and thus holds the door open. To shut the door, all that is necessary is to raise the arm J slightly, when the latch P will be released and the door shut. When the locomotive collides with another object, or runs off the track, &c., the ball 65 C drops from the socket, and thus causes the cord, wire, or chain to pull the bolt M upward, thereby releasing the casing G. The spring H swings the arm J downward in the direction of the arrow a' into the position shown in Fig. 70 1. If the door is closed, the part or bend J' of the arm J is pressed on the upper side of the door and holds the same closed, and thus locks it. If the door is open, the arm J closes it, and then locks it in the manner described. 75 The flames, fire, &c., cannot issue from the fire-door opening, and cannot set fire to the cab and endanger the lives of the engineer and fireman.

Having thus described my invention, I claim 80 as new and desire to secure by Letters Patent—

1. The combination, with a locomotive fire-door, of a spring-actuated arm adapted to lock, or close and lock, the door, and of means for automatically releasing the said arm, substantially as herein shown and described.

2. The combination, with a locomotive fire-door, of an arm formed on a casing containing a spring, means for locking the casing to hold the arm raised, and means for automatically releasing the casing, substantially as herein shown and described.

3. The combination, with a locomotive fire-door, of an arm formed on a casing containing a spring, a bolt for locking the casing in place, and means for automatically withdrawing the bolt, substantially as herein shown and described.

4. The combination, with a locomotive fire-door, of an arm formed on a pivoted casing 100

containing a spring, a bolt for locking the casing in place, and a ball or weight connected by a cord, wire, or chain with the said bolt, substantially as herein shown and described.

- 5 5. The combination, with the casing G, having an arm, J, and containing a spring, H, of the tubular standard A, the cup-shaped socket B on the top of the standard, the bolt M, the ball C, connected with the bolt by a cord, wire, 10 or chain, N, and of the stud L on the casing, substantially as herein shown and described.

6. The combination, with the locomotive-door O, of the latch-lever P, the pivoted casing G, having an arm, J, the spring H, the bolt M in a tubular standard, the socket B, 15 and the ball C, connected with the bolt M by a cord, wire, or chain, N, substantially as herein shown and described.

LEWIS B. WHITE.
